(57) **CLAIM**

We claim the ornamental design for bottle, as shown.

DESCRIPTION

FIG. 1 is a perspective view of a bottle showing our new design;

FIG. 2 is a front view of the bottle depicted in FIG. 1, the opposite side being identical;

FIG. 3 is a side view of the bottle depicted in FIG. 2, representing a ninety degree rotation of the bottle about its vertical center axis from the front view depicted in FIG. 2, the opposite side being identical;

FIG. 4 is a top view of the bottle depicted in FIG. 2; and, FIG. 5 is a bottom view of the bottle depicted in FIG. 2.
